UNITED STATES PATENT OFFICE.

BENJAMIN R. JOLLY, OF RALEIGH, NORTH CAROLINA, AND PRESTON L. FOWLER, OF NEW YORK, N. Y.; SAID FOWLER ASSIGNOR TO SAID JOLLY.

DESIGN FOR A BUTTON, BADGE, OR SIMILAR ARTICLE.

47,303.

Specification for Design.

Patented May 4, 1915.

Application filed December 8, 1914. Serial No. 876,149. Term of patent 3½ years.

To all whom it may concern:

Be it known that we, BENJAMIN R. JOLLY and PRESTON L. FOWLER, both citizens of the United States, and residents, respectively, of Raleigh, in the county of Wake and State of North Carolina, and the city of New York, borough of Brooklyn, in the county of Kings and State of New York, have invented a new, original, and ornamental Design for Buttons, Badges, or Similar Articles.

Reference is to be had to the accompanying drawing in which the figure is a plan view of the button showing our new design.

We claim:

The ornamental design for a button, badge, or similar article, as shown.

BENJAMIN R. JOLLY.
PRESTON L. FOWLER.

Witnesses:

A. L. KITCHIN,
G. H. EMSLIE.
